CLAIM

The ornamental design for a bait station, as shown and described.

DESCRIPTION

FIG. 1 is a top, front, and left isometric view of an ornamental design for a bait station;

FIG. 2 is a front elevational view of the bait station of FIG. 1;

FIG. 3 is a rear elevational view of the bait station of FIG. 1;

FIG. 4 is a right side elevational view of the bait station of FIG. 1;

FIG. 5 is a left side elevational view of the bait station of FIG. 1; and,

FIG. 6 is a top plan view of the bait station of FIG. 1.

The dash-dash-dash broken lines are included for the purpose of illustrating portions of the bait station that form no part of the claimed design. The oblique shade lines depict a transparent or translucent surface or material.
